UNITED STATES PATENT OFFICE

2,047,053

REFRIGERATING MACHINE

Robert U. Berry, Schenectady, N. Y., assignor to
General Electric Company, a corporation of
New York

Application December 5, 1934, Serial No. 756,111

8 Claims. (Cl. 62—136)

My invention relates to refrigerating machines utilizing a refrigerant which remains gaseous throughout the refrigerating cycle, and including a compressor.

5 Refrigerating machines of the type in which a gaseous refrigerant, such as air is employed, and in which the gas is compressed and cooled without liquefaction and then expanded to produce refrigeration may include a compressor of a type
10 which requires scavenging pumps or fans to remove the gas from the compressor cylinder after it has been acted on by the compressor. The hot gas which is compressed is blown out of the cylinder and replaced by cooler gas at the same pressure, the hot gas being circulated through a heat exchange device where its temperature is lowered. The cooler gas is then expanded in the compressor and thereby further cooled and at the end of the expansion stroke is displaced through operation
15 of the scavenging pump by warmer gas which is returned from the cooling element of the refrigerating machine, the displaced cool gas being circulated at constant pressure to the cooling element from the compressor. During each scavenging operation, the compressed or the expanded gas is removed from the cylinder and replaced by gas at the same pressure but at a different temperature. For ideal operation of the refrigerating machine, the scavenging should completely
20 replace the gas in the cylinder with an exactly equal volume of scavenging gas without any mixing of replaced and scavenging gases. It is, therefore, desirable that this scavenging be accomplished in as short a time as possible with
25 little mixing of the scavenging gas and the gas which has been acted on by the compressor.

Accordingly, it is an object of my invention to provide a compressor for refrigerating machines of the type using a gaseous refrigerant without liquefaction which shall have an improved arrangement for scavenging.

Further objects and advantages of my invention will become apparent as the following description proceeds and the features of novelty
45 which characterize my invention will be pointed out with particularity in the claims annexed to and forming a part of this specification.

For a better understanding of my invention, reference may be had to the accompanying drawing, in which Fig. 1 shows diagrammatically a refrigerating system utilizing a compressor and embodying my invention, the compressor being shown in the high pressure scavenging position; and Fig. 2 shows the compressor of Fig. 1 in the low pressure scavenging position.

Referring now to the drawing in Fig. 1, I have shown a refrigerating system of the type in which a gaseous refrigerant is circulated without liquefaction. This system comprises a compressor 10, a heat dissipating coil 11, which is air or water cooled, for removing heat from the compressed gas, and a refrigerating coil 12 for absorbing heat from a medium to be cooled. The coil 11 is arranged in the high pressure circuit of the system and the coil 12 is arranged in the low pressure circuit of the system, scavenging fans or pumps 13 and 14 being arranged to circulate the gas through the high and low pressure circuits respectively. During the operation of the compressor 10, the compressed gas discharged therefrom is at a higher temperature than the gas cooled in the coil 11, which replaces the compressed gas during the scavenging operation. It will thus be seen that the weight of the replacing gas will be greater than that of the replaced gas 20 since both occupy the same volume in the compressor. At the other end of the stroke cold expanded gas is replaced by warmer gas at the same pressure. The gas remaining in the cylinder at the end of the scavenging operation, 25 therefore, has less weight than the removed gas, so that during the operation of the compressor, gas is continually removed from the high pressure side and added to the low pressure side. In order to compensate for this pumping of gas to 30 the low pressure side, another compressor 15 is provided to pump gas from a connection 16 on the low pressure side at the warm end of the refrigerating coil 12 to the connection 17 on the high pressure side at the hot end of the coil 11. 35

It is desirable, as has been pointed out, that during the scavenging operation the gas blown through the cylinder should circulate through the cylinder from one port to the other, with minimum turbulence and little mixing of the gas 40 within the cylinder and the replaced gas. An ideal condition would be attained if there were no mixing whatsoever and the gas in the cylinder were replaced as a body by an equal volume of gas from the scavenging port.

In accordance with my invention, I provide a baffle within the compressor so arranged that the passage of the scavenging gas flowing through the compressor is of substantially uniform cross-section and having an area substantially equal to 50 that of the ports. In the particular embodiment of my invention shown, the compressor 10 comprises a cylinder 18 provided with low pressure ports 19 and 20, and with high pressure ports 21 and 22. Within the cylinder 18 is arranged a 55

reciprocating piston 23 driven by a suitable power device through a reciprocating shaft 23a. The piston 23 is provided with a hollow cylindrical extension 24. When the piston is in the position shown, the end of the extension 24 closes the ports 19 and lies within an annular recess 25 formed by a cylindrical portion 26 extending inwardly from the head of the cylinder 18. Ports 27 and 28 are provided in the extension 24 near the body of the piston 23, and, in the position shown in Fig. 1, these ports register with the ports 21 and 22 respectively in the cylinder. The piston is shown in its position during the scavenging operation at the end of the compression stroke. Scavenging gas is forced by the fan 13 through the coil 11 where it is cooled, then through a conduit 29 to the port 21, through the port 27 into the cylinder 18 and forces the compressed gas out of the cylinder through the ports 28 and 22, and thence to the fan 13 through a conduit 30, as indicated by the arrows in the drawing. The hot compressed gas is thus replaced by cooled gas at substantially the same pressure. In order to provide a path of uniform cross-sectional area for the scavenging gas, I provide a baffle 31 formed at the end of the body portion of the piston 23 and extending partially within the cylindrical portion 24, the baffle extending completely across the cylinder midway between the ports 27 and 28. The chamber formed between the cylinder and the piston at the end of the compression stroke is of U-shape cross-section and of substantially the same area as that of the ports 27 and 28. When the scavenging gas passes through the cylinder there will be a minimum of turbulence and mixing of the scavenging and the replaced gas. From the position shown, the piston 23 moves to the right toward the other end of its stroke, the ports 21 and 22 are closed by the cylindrical portion 24 and the gas is expanded. At the end of this expansion stroke, the ports 19 are uncovered by the cylindrical portion 24 of the piston 23 and the ports 20 register with the ports 27 and 28, as shown in Fig. 2. The cold gas within the cylinder is then forced out through the ports 20 by operation of the fan 14, which blows scavenging gas warmed in cooling coil 12 and at substantially the same pressure through a conduit 32 and the ports 19 into the cylinder. The cooled expanded gas flows through a conduit 33 to the refrigerating coil 12 where it is warmed upon absorption of heat from the medium to be cooled. The ports 19 have a total area substantially equal to that of the cylinder cross-sectional area, and the sum of the areas of the ports 27 and 28 is also substantially equal to the cylinder cross-sectional area. There is, therefore, a minimum mixing and turbulence of the low pressure gas passing through the cylinder.

During the operation of the refrigerating machine herein described the piston 23 and the scavenging fans are operated continuously to deliver hot compressed gas to the high pressure circuit and cold expanded gas to the low pressure circuit. The hot compressed gas delivered to the high pressure circuit by the scavenging operation is cooled in the coil 11 which may be arranged so that a cooling medium such as water or air circulates thereover and the cooled gas from the high pressure circuit is then delivered to the compressor 10 where it is expanded and cooled. The cold gas is delivered to the coil 12 by the scavenging operation and absorbs heat

from the medium surrounding the coil, and when it has been warmed by this absorption of heat is returned to the compressor to complete the cycle of the refrigerating machine. The compressor 15 is operated continuously to maintain the desired pressure difference between the high and low pressure circuits. The dimensions of the ports and the arrangement of the baffle 31 and the cylindrical extension 24 are such that the scavenging gas forces out the gas within the cylinder substantially as a body and, therefore, with very little mixing of the scavenging gas and the gas in the cylinder. The losses due to mixing of gases at different temperatures are thereby minimized, and the efficiency of the scavenging operation is greatly improved.

It will be evident from the foregoing that I have provided a compressor for refrigerating systems in which gaseous refrigerant is compressed without liquefaction, which is so constructed that the scavenging operation will be effected with a minimum turbulence and mixing of the scavenging gas and the replaced gas.

While I have shown a particular embodiment of my invention, other modifications will be apparent to those skilled in the art. I do not, therefore, desire my invention to be limited to the specific construction shown and described and I intend in the appended claims to cover all modifications within the spirit and scope of my invention.

What I claim as new and desire to secure by Letters Patent of the United States is:

1. In a refrigerating machine in which a gaseous refrigerant is utilized without liquefaction, a compressor comprising a cylinder having inlet and exhaust ports, a piston within said cylinder, means operable upon the opening of said intake and exhaust ports for scavenging the gas from said cylinder, and means within said cylinder for providing a passage of substantially uniform cross-sectional area for said scavenged gas flowing between said ports.

2. In a refrigerating machine in which a gaseous refrigerant is utilized without liquefaction, a compressor comprising a cylinder having inlet and exhaust ports, a piston within said cylinder, means operable upon the opening of said intake and exhaust ports for scavenging the gas from said cylinder, and means including a baffle secured to said piston for providing a passage of substantially uniform cross-sectional area for said scavenged gas flowing between said intake and exhaust ports.

3. In a refrigerating machine in which a gas is expanded and compressed without liquefaction, a compressor comprising a cylinder having intake and exhaust ports, and means including a piston for compressing gas within said cylinder, means for scavenging the compressed gas from said cylinder, and means within said cylinder for providing a passage of substantially uniform cross-sectional area for said scavenged gas flowing between said ports.

4. In a refrigerating machine in which a gas is expanded and compressed without liquefaction, a compressor comprising a cylinder having high pressure intake and exhaust ports and low pressure intake and exhaust ports, means including a piston for compressing and expanding gas within said cylinder, means for scavenging the compressed and expanded gas from said cylinder, and means within said cylinder for providing a passage of substantially uniform cross-sectional area

for said scavenged gas flowing between said intake and exhaust ports.

40 7. In a refrigerating machine in which a gas is expanded and compressed without liquefaction, a compressor comprising a cylinder having a low

pressure intake port at one end and a low pressure exhaust port at the other end, said cylinder also having high pressure intake and exhaust ports intermediate said low pressure intake and exhaust ports, means including a piston for compressing gas in said cylinder, means including a hollow cylindrical extension on said piston for closing said low pressure ports on the compression stroke of said piston, the other of said low pressure ports being closed by said piston, means admitting high pressure gas to said cylinder for scavenging said compressed gas near the end of said compression stroke, and means including a baffle and an annular channel at one end of said cylinder for providing a passage for said scavenging gas of substantially uniform cross-sectional area, a substantial portion of said cylindrical extension lying within said channel at the end of the compression stroke of said piston.

8. In a refrigerating machine in which a gas is expanded and compressed without liquefaction, a compressor comprising a cylinder having high pressure intake and exhaust ports and low pressure intake and exhaust ports, means including a piston for compressing gas within said cylinder, means for scavenging compressed gas from said cylinder near the end of the compression stroke of said piston, means for scavenging expanded gas from said cylinder near the end of the expansion stroke of said piston, and means including a baffle on said piston for providing a passage of substantially uniform cross-sectional area for said scavenging gas between said high pressure intake and exhaust ports, the path of said scavenging gas at the end of said compression stroke and at the end of said expansion stroke being of substantially the same cross-sectional area as the high pressure ports and the low pressure ports respectively.
